UNITED STATES PATENT OFFICE.

HENRY WELLEN, OF NEW YORK, N. Y.

DESIGN FOR A BOW-CLASP OR SIMILAR ARTICLE.

59,050.

Specification for Design.

Patented Sept. 13, 1921.

Application filed February 3, 1921. Serial No. 442,310. Term of patent 7 years.

To all whom it may concern:

Be it known that I, HENRY WELLEN, a citizen of the United States, residing at New York, county and State of New York, have invented a new, original, and ornamental Design for Bow-Clasps or Similar

Articles, of which the following is a specification, reference being had to the accompanying drawing, forming part thereof.

The figure is a plan view of a bow clasp showing my new design, and wherein the heavy black bands represent enamel. As

represented in dotted lines, my design is capable of being used in connection with other articles than bow clasps, as, for example, a stick pin, ring or cuff links, or similar articles of jewelry.

I claim:

The ornamental design for a bow clasp or similar article, as shown.

In testimony whereof I have hereunto set my hand on this 29th day of January, A. D. 1921.

HENRY WELLEN.
